UNITED STATES PATENT OFFICE.

JOHN ALLEN HEANY, OF FLINT, MICHIGAN, ASSIGNOR, BY MESNE ASSIGNMENTS, TO
A. E. L. LECKIE, OF WASHINGTON, DISTRICT OF COLUMBIA.

COMBINED GENERATING AND STARTING APPARATUS FOR GAS-ENGINES.

1,117,378.

Specification of Letters Patent.

Patented Nov. 17, 1914.

Application filed July 28, 1910. Serial No. 574,215.

To all whom it may concern:.

Be it known that I, JOHN ALLEN HEANY, a citizen of the United States, and a resident of Flint, in the county of Genesee and State of Michigan, have invented certain new and useful Improvements in Combined Generating and Starting Apparatus for Gas-Engines, of which the following is a full, clear, and exact description, whereby any one skilled in the art may make and use the same.

The invention relates to ignition and lighting systems to be used in connection with prime-movers such as internal combustion engines and more particularly to a simple and compact arrangement of parts which will provide for ignition and other load circuits and in addition thereto may be utilized for giving an initial movement for starting the main prime-mover. More specifically, it relates to a device similar to that set forth in my former Patent No. 979,003, dated Dec. 20, 1910, although it has additional features of advantage in that through a series of clutches and driving devices a maximum torque may be secured for starting the isolated unit and through the combined clutches, this starting movement may be utilized in conjunction with the movement of the unit to give a very much increased driving effect upon the shaft of the engine to be started. A series of effects may be secured, in the driving and driven actions of the dynamo electric machine and the unit connected therewith, through the combination of clutch devices and driving devices hereinafter described.

The objects of the invention are to provide a complete unit, which may be operated entirely independently of the main engine or other device, to which the ignition and load circuits are an appurtenance and which will serve as a powerful driver for starting the main prime mover.

A further object is to utilize unit-parts (that is, the isolated prime-mover and dynamo electric machine) of very small design which will occupy practically no more space than the ordinary magneto commonly used in connection with internal combustion engines and yet will be effective for lighting purposes, ignition and load circuits and for starting the comparatively large main prime mover or engine.

A still further object is to combine the iso-

lated driving unit and dynamo electric machine through a single set of driving connections, which connections may be varied as to the unit and dynamo electric machine and may still be used as the driving connections between one or both of said parts and the main shaft of the engine to be started.

Referring to the drawings: Figure 1 is a horizontal sectional view through the casing containing the driving and clutch parts and dynamo electric machine, the prime mover being shown in plan. Fig. 2 is a view in side elevation looking from the upper side of Fig. 1. Fig. 3 is a detail view of the planetary gear arrangement illustrated in Fig. 1. Fig. 4 is a perspective view of the operating shafts for the clutches. Fig. 5 is a diagrammatic view illustrating the various parts of the mechanism and one form of electrical connections.

In carrying out the present invention which is somewhat analogous to the invention of the co-pending application hereinbefore referred to, provision has been made for utilizing the dynamo electric machine and the prime-mover connected therewith through driving mechanism which will give a large ratio between the driving and driven parts. The same driving mechanism may, through suitable clutch devices, be utilized between the dynamo electric machine and prime-mover and between either or both of said parts and the main prime-mover or engine, which is to be started. The whole mechanism forms a compact unit which may be applied to such an engine as is employed upon automobiles or the like, occupying no more space than the ordinary magneto. With such an arrangement, a very small dynamo-electric machine may be used which will have, through the driving mechanism, a sufficient driving effect to initially start the prime-mover and said prime-mover may therefore be made of a convenient size to act either alone or in conjunction with the dynamo electric machine for starting the main prime-mover or engine, in as much as the drive takes place through gears which give a maximum effect. It is also possible to actuate the dynamo electric machine from the prime-mover of the unit or from the main prime-mover.

From the above it is apparent that various combinations of drive may be secured in a

single unit and as hereinafter described any of the desired effects may be secured through a single controlling apparatus.

Referring to the drawings the numeral 1, 5 denotes the armature of the dynamo electric machine having a commutator 24, suitable brushes 20, and fields 21, mounted within a substantially tubular casing 23, which provides proper bearings for a shaft 11. 10 The armature and appurtenant moving parts are mounted on a sleeve 25, which surrounds the main shaft 11, that is connected with and is an extension of the crank shaft of the prime-mover 12, the cylinder of which 15 is indicated at 26. Secured to the sleeve 25, at one end is a male clutch-part 2, which may be engaged and disengaged through a lever 18, with the female clutch-part 3, that is provided with an extended sleeve 3^a. The 20 opposite end of the sleeve 25, has keyed to it a female clutch-part 13, which may be engaged and disengaged by a male clutch-part 14, through a suitable lever 19. The male clutch-part 14, is keyed to slide upon the 25 shaft 11, while the male clutch-part 2, is similarly arranged upon the sleeve 25.

At the extreme end of the shaft 11, and axially movable thereon is a male clutch-part 10, controlled by a suitable lever 17, 30 for engagement and disengagement with the female clutch-part 9. This latter member is integrally formed or properly connected with an internal gear 8, which has on its exterior a band-brake 15, controlled by a 35 suitable lever 15^a. Axially arranged with reference to the gear 8, is a similarly formed gear 7, which is loosely mounted upon the sleeve 3^a. Within both of the gears 7, and 8, there is arranged a spider 5, which bears 40 a pinion 6, that meshes with the teeth of both the internal gears. This spider is keyed to the sleeve 3^a, through a key 4. The gear 7, has properly formed on its exterior side gear-teeth 7^a, with which meshes a gear 45 16, which is properly arranged through intermediates to drive the main engine 16^a. The internal gears 7, and 8, have a different 50 number of teeth. As designed herein, there is a difference of one tooth in favor of gear 7 so that there will be a planetary reduction action in the operation of said gears in conjunction with the pinion 6.

With this arrangement of parts, the following combinations are possible. To start 55 the prime-mover by means of current from the storage battery, the clutch parts 2, and 3, are connected and the clutch-parts 9, and 10, are caused to engage. It follows that the armature sleeve 25, will drive through 60 the clutch-parts 2, 3, grid 5, pinion 6, gear 8, clutch-parts 9, and 10, and the main shaft 11, thus turning over said shaft and giving the initial impulse to the prime-mover 12 under the highest torque value. Of course,

it is understood that the gear 7, in this instance, is held against movement, being connected with the shaft of the main prime-mover. To start the main prime-mover after starting the unit prime-mover 12, and utilizing the force of the rotating armature 70 when the clutch-parts 13, 14, are engaged, the clutch-parts 2, and 3, are left in engagement, the band-brake 15, is engaged with the gear 8, and the clutch-parts 9, and 10, are opened. Assuming the unit prime mover 75 12 to be in operation in order to start the main prime mover using only the unit prime mover 12, the clutches 13, 14, 2 and 3 are engaged and the drive will be transmitted through 3, 4, 5, and 6, to 7 and 8. The brake 80 15 is now applied and will prevent 8 from revolving. Whereupon the gear 7 will receive motion and transmit same to the engine shaft through the gear 16 and appurtenant parts. To operate the dynamo electric machine from the unit prime-mover 12, the clutch-parts 13, 14, are closed, while the clutch-parts 2, and 3, and 9, and 10, with the band-brake 15, are released. This gives a direct drive between the prime-mover 12, 90 and dynamo electric machine for furnishing ignition, lighting and storage current. If, for any reason, the unit prime-mover 12, is not available for running the dynamo electric machine, it is possible to drive the armature directly from the main engine after it has been started. This is effected by closing the clutch-parts 13, 14, 2, 3, 9, and 10, and opening the band-brake. 95

From the above, it is apparent that almost 100 any desired combination of driving effects may be secured and the same reduction gears may be employed in the various combinations.

As illustrating a means for controlling 105 the position of the various clutches, there is shown in Fig. 2, a rotary and axially movable rod 30, provided with a series of keys so spaced that any of the several levers 31, 32, 33, 34, may be engaged and turned to rock the respective shafts 35, 36, bell-crank-lever 37, and shaft 38, these parts being respectively connected with the lever-arms 19, 18, band-brake 15, and lever-arm 17. Obviously, any desired 110 arrangement might be utilized for operating the several levers to secure the proper clutch connections herein described as being of simple form. By shifting the shaft 30, axially, it may be positioned to pick up 120 and engage the several levers for giving any desired combination. By then partially rotating the shaft, the desired clutching and releasing actions will be effected.

In the diagrammatic view illustrated in 125 Fig. 5, the unit is illustrated in conjunction with a storage battery A, a switch device B, which controls the circuit of the dynamo

electric machine with reference to the storage battery and the load or lamp circuit C, and ignition circuit D.

Any desired form of ignition may, of course, be used and as illustrated herein, there is a simple form of jump-spark.

In practice, it is preferable to use a dynamo electric machine having a shunt-field winding in conjunction with a series field winding, thus providing a field excitation of opposed character to that of the shunt winding and one which is always less than the latter.

With such a machine, as the armature speed increases and the electro-motive force increases, the armature and series winding will vary, thus increasing the field excitation through the series coil which is opposed to the shunt field windings and consequent excitation. The resultant field will be reduced since the electro-motive force of the generator is substantially proportional to the product of the armature speed and field strength any increase in speed tending to increase the electro-motive force will produce a decreased field strength, thus maintaining a substantially constant electro-motive force. The machine will operate as a differentially wound generator and as a compound wound motor. Thus a maximum starting torque may be secured when running as a motor and a substantially constant electro-motive force will be secured

even though the armature be driven from the shaft of the main prime-mover or engine which has a variable speed. Of course, when driven under the constant speed conditions of the unit prime-mover, the electro-motive force will always be constant.

Obviously, various details of the arrangement described might be varied to suit the exigencies of any particular case, the main object, however, is to secure a unit comprising a prime-mover and dynamo electric machine with a system of driving connections and control by which it is possible to utilize comparatively small parts with maximum driving effects with reference to each other.

What I claim as my invention and desire to secure by Letters Patent is:

In combination, a main engine, a smaller auxiliary engine, an electric plant including a motor dynamo and a storage battery and suitable circuits, means whereby the auxiliary engine may drive the motor dynamo direct for generation of current, means whereby the motor dynamo may drive the auxiliary engine indirectly, and means whereby the auxiliary engine after it is started by the motor dynamo may drive the main engine, for the purposes set forth.

JOHN ALLEN HEANY.
